I claim the ornamental design for a snuffer tool, as shown and described.

DESCRIPTION

FIG. 1 is a perspective view of a snuffer tool, showing my new design;

FIG. 2 is a front elevational view of FIG. 1;

FIG. 3 is a rear elevational view of FIG. 1;

FIG. 4 is a right-side elevational view of FIG. 1;

FIG. 5 is a left-side elevational view of FIG. 1;

FIG. 6 is a top plan view of FIG. 1;

FIG. 7 is a bottom plan view of FIG. 1; and,

FIG. 8 is a cross-sectional view of FIG. 4, taken along line 8-8.

The broken lines showing a cigarette lighter in FIG. 1 depict environmental matter and form no part of the claimed design.
